UNITED STATES PATENT OFFICE.

ANDREW SMITH, OF MILWAUKEE, WISCONSIN.

OIL-PAN CONSTRUCTION.

Application filed December 5, 1924. Serial No. 754,113.

To all whom it may concern:

Be it known that I, ANDREW SMITH, a citizen of the United States, and resident of Milwaukee, in the county of Milwaukee and State of Wisconsin, have invented certain new and useful Improvements in Oil-Pan Constructions; and I do hereby declare that the following is a full, clear, and exact description thereof.

10 This invention relates to oil pans for internal combustion engines.

In internal combustion engines, it is the customary practice to draw the oil from the oil pan, but if this intake is positioned low enough to insure an adequate supply of oil thereto at all times there is also danger of drawing in sediment and harmful material and carrying such matter in the oil stream to the several bearings.

20 This invention is designed to overcome the above noted defects, and objects of such invention are to provide an oil pan construction and associated mechanism which is so formed that means are provided for separating out the sediment during the quiet periods of the engine and for closing off the sediment chamber in an automatic manner during the active periods of the engine to thus prevent sediment finding its way into the oil stream and yet permit the placing of the oil intake sufficiently low to insure an adequate supply of oil thereto at all times.

Further objects are to provide automatic means for controlling communication between the sediment chamber and oil pan and to so construct this automatic mechanism that it will be positive in its operation and responsive to oil pressure and will be wholly reliable and substantially fool proof.

40 Further objects are to provide means for yieldingly urging a transverse slide towards a closed position whenever oil pressure exists in the lubricating system so that if for any reason the slide should freeze tight to the stationary member breaking of the parts will not occur, and yet when the engine warms up sufficiently to free the slide, such pressure will effectively act upon the slide and move it to closed position.

50 Further objects are to provide means for removing sediment from the oil pan throughout the major portion of the extent of the oil pan and to provide means for guiding the sediment into the appropriate passages leading to the sediment chamber.

An embodiment of the invention is shown

in the accompanying drawings, in which:

Figure 1 is a longitudinal section through the oil pan showing the operating mechanism partly broken away.

60 Figure 2 is a transverse sectional view through the oil pan, such view corresponding to a section on the line 2—2 of Figure 1.

Figure 3 is an enlarged fragmentary plan view of a portion of the slide and associated parts.

Referring to the drawings, it will be seen that the oil pan 1 for the crank case is provided with a sediment chamber or sump 2 which is separated off from the oil pan by 70 means of a transverse partition 3. This transverse partition is provided with a plurality of regularly spaced apertures 4 which place the sump or sediment chamber 2 in communication with the oil pan. Immediately above the partition 3 or stationary plate, a slide 5 is provided and guided by suitable members 6 secured to such plate. This guide 5 is provided with a plurality of apertures 7 which register with the apertures 4 in 80 the plate 3 when the slide is in one extreme position of adjustment, as shown in the figures of the drawing.

The plate 3 is provided with upstanding pins or stops 8 which limit the motion of the slide, and in this connection it has been found expedient to provide the slide with reinforcing upturned flanges at its ends adapted to contact with such pins. The slide is further provided with an upstanding apertured ear 9 which receives a closing spring 10, the other end of such spring being connected to a lug carried by the oil pan 1. The spring 10, when it is effective, opens all of the apertures and places the interior 90 of the oil pan in communication with the sediment chamber.

It is to be noted particularly that the slide 5 is provided with ribs 11 which are positioned between successive rows of apertures 100 7 and are of substantially inverted V-shaped or wedge-shaped formation so as to guide any falling sediment into the apertures and prevent its lodging upon the slide 5. The ends of the ribs 11 are pinched together, as shown clearly at 12 in Figure 2, to prevent the accumulation of trash beneath such ribs which might in time interfere with the smooth action of the slide.

110 A plurality of transverse oil troughs 12 are secured to the oil pan 1 and are adapted to carry oil and to lubricate the cranks and

pitmen and other adjacent parts by the dipping of the pitmen or crank into this oil. These troughs are fed from a header 13 positioned within the crank case, as shown in Figures 1 and 2, and provided with a plurality of ports connected by means of small pipes 14 and 15 with the several oil troughs. The header is equipped with an outwardly projecting inlet portion 16 to which the fresh oil is fed by a suitable pump in the usual manner. The lower portion of this header 13 is formed into a cylinder 17 which receives a piston 18. The piston is relatively elongated and is provided with a portion of reduced diameter, as indicated at 19, and with an upper portion 20 provided with bleed notches 21 for a purpose hereinafter to appear. The piston is freely slideable in the cylinder 17 and is held upwardly when the engine is idle by means of an arm 22 of a bell crank lever, such bell crank lever having its other arm connected by means of a spring 23 with the ear 9 of the slide 5, as clearly shown in Figure 1.

It is, of course, understood that the sediment chamber 2 is provided with a suitable drain plug 24 to permit the ready removal of accumulated material.

In operation, when the engine is idle and no pressure exists in the header 13, the slide occupies the position shown in the drawings, and is against the left hand pins 8, being held in such position by the spring 10. Communication is thus maintained between the oil pan and the sediment chamber and sediment is guided by the ribs 11 through the apertures into the sediment chamber. When, however, the engine is started, the oil pressure immediately builds up and forces the piston 18 downwardly, thus depressing the bell crank lever arm 22 and tensioning the spring 23. The spring 23 may be relatively heavier than the spring 10 and thus overcomes the spring 10 and moves the slide 5 to the right, thus shutting off communication between the oil pan and the sediment chamber. When the engine is stopped the piston 18 moves upwardly and the slide is restored to its initial position.

It is to be noted that the bleed notches 21 permit the slide to move upwardly although the oil pressure may temporarily exist in the oil system. In other words, oil is not trapped in the header 13 by the piston 18 when the engine has stopped, but such oil is allowed to slowly pass through the bleed apertures or notches 21 and the slide is therefore permitted to move back to its initial position.

The purpose of the spring 23 is to provide a yielding connection between the piston and the slide. One of the advantageous features resulting from this construction is that during cold weather when the oil is very thick and almost hard, or when the slide 5 freezes

to the plate 3, it would be impossible for the piston to operate if it were rigidly connected to the slide. However, under these conditions, the piston moves downwardly and permits free flow of the oil to the delivery pipes 15 and 14 and tensions the spring 23. As soon as the oil warms up sufficiently, the slide moves to the right under the action of the spring 23.

It will be seen, therefore, that even under the most adverse conditions, no damage or interference with the smooth and practical operation of the device can result, and it will be noted further that the device is protected at all times from damage, as all parts thereof are housed within the crank case.

It is to be further noted that no change need be made in other portions of the oil system as the delivery pipe leading to the header may be connected to the inlet portion 16 in the usual manner.

It will be seen, therefore, that an extremely simple, reliable and effective construction has been provided for controlling communication between the oil pan and the sediment chamber, and it will be seen further that the improved oil pan construction may be most easily applied to existing types of motors without change of construction.

It is to be noted further that in the types of engines where transverse oil troughs are not employed for the cranks that, obviously, the cylinder 17 and header 13 need not employ the outlet ports. These ports may, of course, be closed under such conditions and the device will operate in the manner described when it is connected to an appropriate point in the oil pressure system.

It will, therefore, be seen that a very simple effective and universally applicable construction is provided and that the device is positive and certain in its operation and is not likely to get out of order.

Although the invention has been described in considerable detail, it is to be understood that the invention may be variously embodied and is, therefore, to be limited only as claimed.

I claim:

1. The combination of an internal combustion engine oil pan, a sediment chamber connected with the lower portion thereof, an apertured stationary member interposed between said chamber and oil pan, an apertured slide positioned upon said stationary member, a spring urging said slide in one direction to permit registering of the apertures, and a piston operated by the oil system of the engine, said piston being operatively connected to said slide and adapted to move said slide towards aperture closing position when pressure exists in the oiling system.

2. The combination of an internal combustion engine oil pan, a sediment chamber

mounted therebelow, and separated therefrom by a transverse stationary partition provided with a plurality of apertures, a slide carried by said partition and having 5 corresponding apertures therein, a spring urging said slide towards a position to permit registration of apertures, an oil cylinder adapted to be connected to the lubricating system of the engine, a piston mounted 10 within said cylinder and movable under the influence of oil pressure, mechanism connected with said piston and operated therefrom, and a connecting member joining said mechanism and said slide.

15 3. The combination of an internal combustion engine oil pan, a sediment chamber mounted therebelow, and separated therefrom by a transverse stationary partition provided with a plurality of apertures, a 20 slide carried by said partition and having corresponding apertures therein, a spring urging said slide towards a position to permit registration of apertures, an oil cylinder adapted to be connected to the lubricating 25 system of the engine, a piston mounted within said cylinder and movable under the influence of oil pressure, mechanism connected with said piston and operated therefrom, and a spring yieldingly connecting said 30 mechanism and said slide.

4. An oil pan construction for internal combustion engines comprising a main chamber, a sediment chamber therebelow divided from said main chamber by a stationary apertured partition, a slide mounted 35 upon said partition and having apertures therein adapted to register with the apertures in the partition when the slide is in one extreme position, a spring urging the 40 slide towards aperture opening position, a cylinder carried by said oil pan, and adapted to be connected to a suitable source of oil pressure, a piston mounted within said cylinder, a bell crank having one arm operatively associated with said piston, and a spring connecting the other arm of said bell crank lever with said slide.

ed within said cylinder, a bell crank having one arm operatively associated with 45 said piston, and a spring connecting the other arm of said bell crank lever with said slide.

5. An oil pan construction for internal combustion engines comprising a main 50 chamber, a sediment chamber therebelow divided from said main chamber by a stationary apertured partition, a slide mounted upon said partition and having apertures therein adapted to register with the apertures in the partition when the slide is in one extreme position, a spring urging the 55 slide towards aperture opening position, a cylinder carried by said oil pan, and adapted to be connected to a suitable source of oil pressure, a piston mounted within said cylinder, a bell crank having one arm operatively associated with said piston, and a spring connecting the other arm of said bell 60 crank lever with said slide, said slide having a plurality of wedge-shaped ribs interposed between successive apertures, said ribs projecting upwardly and adapted to guide sediment to said apertures.

6. An oil pan construction adapted for 70 use on an internal combustion engine having oil pressure lubrication comprising an oil pan, a sediment chamber associated therewith, a movable member controlling communication between said sediment 75 chamber and said oil pan, and movable pressure responsive means actuated by the pressure of the lubricating oil, said movable means being mechanically connected to said movable member for imparting motion to 80 said member.

In testimony that I claim the foregoing I have hereunto set my hand at Milwaukee, in the county of Milwaukee and State of Wisconsin.

ANDREW SMITH.
